UNITED STATES PATENT OFFICE.

JAMES WILLIAM WILLIS, OF TORONTO, ONTARIO, CANADA.

FLOOR WAXER AND POLISHER.

Application filed November 21, 1923. Serial No. 676,077.

To all whom it may concern:

Be it known that I, JAMES WILLIAM WILLIS, a subject of the King of Great Britain, and resident of the city of Toronto, 5 in the county of York, in the Province of Ontario, Canada, have invented certain new and useful Improvements in Floor Waxers and Polishers, of which the following is the specification.

10 My invention relates to improvements in floor waxers and polishers, and the object of the invention is to devise a simple, light, durable device whereby wax may be evenly distributed upon a floor surface and evenly 15 polished even though the floor boards may be more or less warped, and it consists essentially of the arrangement and construction of parts as hereinafter more particularly explained.

20 Fig. 1 is a perspective view of my device as used for distributing the wax upon a floor surface.

Fig. 2 is a sectional view through Fig. 1 taken from the front to the back of the device.

25 Fig. 3 is a longitudinal sectional view through the wax reservoir.

Fig. 4 is a cross sectional view through Fig. 3.

30 Fig. 5 is a similar view to Fig. 3, with the polishing means inserted in position, and the wax container removed.

Fig. 6 is a cross sectional view through Fig. 5.

35 Fig. 7 is a perspective view of the polishing member removed from my device.

Fig. 8 is an enlarged perspective detail of a portion of my polishing member, showing the means whereby the polishing brushes are locked in position within their container.

40 In the drawings like characters of reference indicate corresponding parts in each figure.

1 and 2 are cross boards or plates secured 45 together at their ends by brackets 3 and 4, so as to space them apart and form a cross-wise extending opening 5. The cross boards 1 and 2, and brackets 3 and 4, form the body of my device.

50 6 and 7 are bale members pivotally secured at 8 to each of the brackets 3 and 4, the inner ends of such members being upturned at 6^x and 7^x.

Between the upturned ends 6^x and 7^x is secured a handle 9 by cross bolts 10.

55 11 and 12 are cross slots formed by the de-

pending portions 12^x and 12°, and in which is inserted edgewise a strip of thick felt, 13, so as to protrude at its lower edge therefrom to contact with the surface of the floor and 60 form wax spreading means.

The board or plate members 1 and 2 extend between the brackets 3 and 4, such brackets being provided with lugs 3^x and 4^x extending over the members 1 and 2, and to 65 which such members are secured by the screws 16. The outer edges of the board or plate members 1 and 2 are provided with strips of felt, 17, to form buffers so as to prevent the scratching or marking of furniture 70 or skirt board with which my device may come in contact during operation.

In the intervening orifice 5 located between the members 1 and 2 I have placed my wax container, the construction of which I 75 will now describe.

18 is a rectangular receptacle, the bottom portion of which converges as indicated at 19, so as to depend through the orifice 5.

20 are lugs which rest upon the upper face 80 of each member 1 and 2 at each end of the opening 5 so as to support the wax container in the aforesaid position. The bottom of the container 18 is provided with a longitudinal slot 21.

22 and 23 are openings formed in the end walls 18^x and 18° of the container at each end of the slotted opening 21.

24 is a covering plate secured by screws 25 to the lower face of the container 18, the 90 lower face of the converging portion 19 being surfaced off for the reception of the covering plate 24.

26 are perforations formed in the covering plate 24 and extending longitudinally beneath the slotted opening 21, as clearly indicated in Fig. 3.

27 is a bar extending at its ends into the openings 22 and 23 and slidable upon the covering plate 24. The bar 27 when carried to 100 a projecting position at the opposite end of the wax container 18, as indicated by dotted lines in Fig. 3, forms a closure for the perforation 26. When the bar is pushed in the opposite direction, that is from right to left, the perforations 28 are carried into a registering position with the perforations 26 so as to permit the wax feeding downward through the line of perforations on to the floor to be polished.

110 29 is a cover for the container.

30 are spring fingers located at each end

of the container bent at their upper ends in V form as indicated at 31, the distance between the apex portion of each V portion 31 being less than the length of the cover 29, therefore, when the cover 29 is forced into its covering position it springs the fingers 30 outward so that the ends of the cover pass the V portions and engage beneath the same when in the covering position.

10 32 is a flange extending from the covering plate fitting within the open top of the container 18 so as to hold the plate in position. In waxing the floor, my device is used as above described, the perforations 28 and 26 being moved into a position so that the wax feeds down on to the floor to be polished. The felt strips 13 bearing upon the floor at their lower edge spreads the wax over the surface of the floor, thereby covering 20 the floor with a thin film of wax. The floor is then left for the required length of time before being polished.

When the floor is ready for polishing, I use my device with the polishing members 25 which I will now describe.

When my device is adapted for polishing the floor, the wax container 18 is lifted out of its position and the polishing member which I will now describe inserted beneath 30 the board or plate members 1 and 2 between the brackets 3 and 4, being held in position by the depending portions 12^x and 12°.

33 is a casing which is rectangular in form and fitting between the brackets 3 and 35 4 and depending portions 12^x and 12°. The open face of the casing depends downward. One end edge of the casing 33 is turned inward, as indicated at 34. The other end edge is provided with an inturned portion 40 forming a groove 35.

36 are a series of cross walls extending crosswise of the casing, dividing the casing into a series of transverse compartments.

37 are bristle brushes provided with backing pieces 38 which fit the transverse compartments formed by the walls 36, one end edge of the backing piece 38 extending over the inturned flange 34, the opposite end edge extending adjacent to the inturned portion 50 35.

39 is an angular strip, one flange of which is slidable longitudinally within the groove 35, the other flange extending horizontally outward from the groove so as to extend beneath the adjacent end edge of the brush backing 38 and thereby support the brush within the compartment of the casing 32.

40 are pressure springs bearing against the backing pieces 38 of each brush 37.

60 41 are the bristles of the brush 37 which engage the surface of the floor for the purpose of polishing it, as hereafter described.

In order to secure the casing 33 in the position above described I have provided 65 the following securing means.

42 is a block secured to the upper wall of the casing 32, such block being located in the orifice 5.

43 is a spring strip pivotally secured to the block 42 by a screw 44 and which when 70 swung transversely of the orifice, engages the edges of the opening 5 formed by the inner edges of the members 1 and 2.

45 is a weight formed of suitable material. The weight 45 is provided on its un- 75 derface at each side of its centre with spaced apart ribs 46 and 47 adapted to fit at each side of the block 42. By this means the spring strip is held in position crosswise of the opening 5 and locked in such 80 position so that it cannot slip out of engagement with the side edges of the opening. The ends of the weight 45 are provided with ribs 48 and 49 whereby the weight is supported so as to be held level 85 upon the casing 33.

It will be noted that the brushes 37 are set in the casing so as to be arranged longitudinally parallel with the direction of 90 travel of the polisher over the surface of

the floor, and also that the pivotal connection of the handle 9 is arranged crosswise of the brushes and that therefore when the device is used upon the floor the polishing is done longitudinally of the boards and the 95 brushes travel longitudinally parallel with such boards, and therefore each brush engages a board individually, so that if there is any depression or crosswise warping of the board, the brush will enter such depression 100 and contact directly with the surface to polish it.

When the device is used for polishing the floor, the felt strips 13 are inverted so that the opposite or clean edge engages with the 105 floor.

From this description it will be seen that I have devised a very simple floor waxing and polishing device which will readily engage the floor so as to polish its whole surface no matter whether the edges of the boards are warped up so as to render the boards slightly convex transversely, or whether such floor surface is even.

I have also provided such a device by 115 which the wax may be evenly spread over the surface of the floor so as to form a thin film prior to polishing.

It may be also pointed out that the weight 45 is removable, the weight merely resting upon the top of the body of my device. When my device is used for polishing the floor, I first use it without the weight until a certain amount of gloss is given to the 120 surface of the waxed floor to permit of the polishing device slipping easily thereover.

When this is done, I then place the weight on the polishing device to complete the polishing process, giving the floor surface 125 a much higher gloss.

It will thus be seen that the labour involved is greatly decreased, as when the floor is freshly waxed it is very much harder to push the polishing device over the surface of the floor with the heavy weight thereon. When the floor is partially polished, as above set forth, the waxer will move more easily over the surface, and therefore the weight can be added to complete the polishing process.

It may also be suggested that in some cases it may be advisable to use the polishing device without the weight, when the person operating the polisher has not sufficient strength to remove the heavy device, and without the weight slight pressure can be put on the handle in order to give the floor the extra gloss.

What I claim as my invention is:

1. A floor waxer and polisher comprising a body having a central crosswise opening, a wax container supported in the opening so as to depend therethrough, means for feeding the wax from the container on to the floor, depending portions extending crosswise from the front and rear edge of the body and grooved longitudinally, and felt strips, one longitudinal edge of which extends into the groove and the other longitudinal edge bears upon the floor surface holding the wax container clear of the floor.

2. In a device of the class described, a wax container having a slotted opening in the bottom extending through the end walls of the container, a perforated covering plate secured to the bottom of the container to extend over the slotted opening, and a perforated slide bar slidable within the slotted opening and adapted to extend alternately through one or other of the end walls of the container.

3. A floor waxer and polisher comprising a body having a central opening and depending groove portions extending from each end, felt strips inserted edgewise in each of such groove portions so as to bear

upon the floor, a polishing member secured within the body between the aforesaid felt strips, and polishing brushes resiliently held within the body and extending between and at right angles to the aforesaid strips.

4. A floor waxer and polisher comprising a body having a central opening, felt strips extending transversely of the body and depending therefrom, a polishing member comprising a casing fitting within the body between the felt strips, means extending through the central opening of the body for detachably securing the casing in position, and a series of individually spring pressed brushes held within the casing and extending longitudinally between the strips.

5. In a device of the class described, a polishing member comprising a casing, a series of polishing brushes arranged parallelly within the casing, individual pressure springs for each brush, and means for detachably securing the brushes within the casing.

6. In a device of the class described, a polishing member comprising a rectangular casing having an inturned forward edged flange, a series of parallel brushes, backing pieces of which are adapted to be supported by the aforesaid flange, and withdrawable means for supporting the opposite ends of the brush backing.

7. In a device of the class described, a polishing member comprising a casing having an inturned forward edge flange, a series of brushes, the backing pieces of which are arranged parallelly within the casing so as to be supported at one end upon the aforesaid flange, a grooved portion formed by the wall at the rear end of the casing, and a bar member slidable within said groove and having an outwardly projecting portion upon which the opposite ends of the brush backings bear, and individual pressure springs bearing against the back of each brush.

JAMES WILLIAM WILLIS.
